UNITED STATES PATENT OFFICE.

HAROLD C. WHITE, OF CLEVELAND, OHIO, ASSIGNOR TO THE GUIDE MOTOR LAMP MANUFACTURING COMPANY, OF CLEVELAND, OHIO, A CORPORATION OF OHIO.

LAMP SOCKET.

Application filed May 1, 1924. Serial No. 710,220.

This invention relates generally to automobile lamps and more particularly to a novel construction of socket employed in connection with said lamp.

- 5 One object of the invention is to provide an exceedingly simple and easily fabricated form of socket which can be used in connection with any of the standard types of lamps.
- 10 Another object of the invention is to provide a socket in which there will be a solid current carrier as distinguished from one in which the current is carried partially by the springs forming a part of the socket.

- 15 Another object is to provide means for taking up the vibration whereby the connection between the socket and the conductor wire is rendered more secure. Other objects of the invention will appear as the 20 description proceeds.

With these various objects in view, the invention consists in the novel features of construction and the manner of combining and arranging the same, all of which will 25 be fully described hereinafter and set forth in the appended claims.

In the drawing forming a part of this specification, Fig. 1 is a view of a lamp partly in section and showing the practical 30 application of my invention; Fig. 2 is an enlarged sectional view partly in elevation; Fig. 3 is a sectional plan view; Fig. 4 is a top plan view of the socket; Fig. 5 is a detailed perspective view of one of the contact plates; Fig. 6 is a detailed sectional 35 view of Fig. 2; Fig. 7 is a rear end view of the socket; and Fig. 8 is a detailed view partly in section showing the manner of connecting the conductor wire to the contact plate.

40 Referring to the drawings, A indicates the usual lamp casing and B the reflector therein. C indicates the incandescent lamp the plug C' of which is inserted in the tubular socket D which in turn is fitted in the sleeve E which is rigidly connected to the reflector B and extends rearwardly, as most clearly shown.

The tubular socket D has an angular rod 45 or plate F connected thereto and through which the adjusting screw G works in order to change the focus of the lamp. This screw G is passed through the rear end of the lamp casing as most clearly shown in

Figs. 1 and 2. A spring G' surrounds the 55 bolt between the depending end of the rod F and the back of the casing. The depending end of the rod is threaded and it is obvious that by turning the screw, the lamp can be moved back and forth in order to 60 focus the same. The tubular socket D has the usual bayonet slots D' and also the friction slots D². By employing friction slots a firmer hold is secured upon the socket of the incandescent lamp.

65 In practice I prefer to shape the tubular socket D from a plate of metal rolled into cylindrical form and having an integral tongue D³ which interlocks with a correspondingly shaped notch D⁴. In addition 70 to the tongue D³ the edges of the plate from which the tubular socket is formed are also provided with outwardly extending tongues D⁵ which are passed through an opening in the forward end of the rod F and bent in 75 opposite directions in order to establish the connection between the tubular socket D and the adjusting rod F. The rear end of the plate is also formed with inwardly projecting lugs D⁷ which serve to hold the insulating disk H adjacent the rear end of 80 the tubular socket and within this tubular socket there is also employed another insulating disk I which disk is formed with lateral lugs or extensions I' which fit into 85 openings I² produced in the sides of the tubular socket.

85 In this manner the insulating disk I is positioned within the tubular socket and is permitted a limited back and forth movement. The insulating plates H and I are provided with parallel registering apertures in which the contact plates K are placed, each contact plate being offset at K' and the plates K are arranged with these 90 offsets in such manner as to space the rear ends K² a considerable distance apart while their forward ends are comparatively close together and held in proper position for contact with the terminals C² of the lamp 100 socket C'. Each plate K is formed with an opening K³, there being oppositely disposed tongues K⁴ extending into said opening for the purpose of positioning the coil springs L which are placed within the opening K³ with the ends thereof contacting with the tongues K⁴. These springs K³ 105 maintain the contact plates in their for-

wardly projecting positions so that a rugged contact between the ends of the plates and the terminals of the socket is always had.

- 5 To the rear end of each contact plate K there is attached a coupling device M by means of which the conductor wires N are connected to the contact plates. These coupling members are bifurcated at their upper 10 ends and through which the screw M² passes, said screw being threaded into the threaded aperture K⁶ in the end of the contact plate. This bifurcated end is upset as indicated at M³ in order to have an enlarged contact upon 15 the end of the contact plate inasmuch as by means of this construction, it can contact with the side as well as the edge of the contact plate.

The lower end of the coupling member M 20 is formed with overlapping ears or lugs M⁴ which securely embrace the insulated conductor wire and in addition to these overlapping lug portions M⁴, the coupling member is also provided with lugs M⁵ which are 25 folded down over the metallic portion N of the conductor and from which the insulation has been removed and in practice it is preferred to complete this connection by a soldered joint so that the electrical conductor is 30 positively and permanently connected to the coupling member.

By having the lower encircling arms or lugs M⁴ contact with the elastic covering of the conductor, the connection is cushioned to 35 a certain extent so that the vibrations to which the lamp is subjected are not communicated to the actual connection between the coupling member and the electric conductor N. By this arrangement the contact is not 40 so liable to crystallize and become broken as in the present method wherein no cushioning effect is obtained.

It will thus be seen that I provide an exceedingly cheap and simple construction of 45 socket made up preferably from a sheet of metal and shaped into a tubular socket in such a manner as to facilitate its connection to the other parts of the lamp. It will also be noted that, owing to the peculiar construction and arrangement of the contact plates, a rugged and secure contact is had at all 50 times between the contact plates and the lamp terminals. The feature of establishing a cushioning connection between the conductor wire and the contact plates is also 55 important as materially prolonging the life of the socket.

Having thus described my invention, what I claim is:—

- 60 1. The combination with a tubular member, of insulating disks arranged therein, contact plates working through said disks, each plate having an opening and lugs at ends of said openings, springs arranged in 65 said openings and positioned upon said lugs,

and means for connecting said plates to the conductor wires.

2. In a device of the kind described, the combination with a tubular member having openings in its sides and inwardly projecting lugs at its rear end, of an insulating disk arranged within the tubular member at the rear end thereof, a second insulating disk arranged within the tubular member and spaced from the first disk, said second disk 70 having laterally projecting extensions fitting into the side openings in the tubular member, both of said insulating disks having spaced openings, contact plates arranged in said openings, each contact plate having an opening, springs arranged within said openings and adapted to maintain the contact plates in their contact positions.

3. The combination with a tubular member having openings in its sides and inwardly projecting lugs at its rear end, of an insulating disk arranged within the tubular member at the rear end thereof, a second insulating disk arranged within the tubular member and spaced from the first disk, said second disk 75 having laterally projecting extensions fitting into the side openings in the tubular member, both of said insulating disks having spaced openings, contact plates arranged in said openings, each plate having a longitudinal opening with oppositely disposed 80 projecting portions at the end of each opening, springs arranged in said openings and positioned by the oppositely disposed lugs, said springs maintaining said contact plates 85 in their contact positions.

4. As a new article of manufacture, a tubular socket member comprising a plate bent into cylindrical form and having an integral tongue interlocking with a correspondingly 90 shaped notch, said tubular member also having oppositely disposed outwardly extending tongues for connection to a rod, said tubular member also having oppositely disposed 95 openings in the sides thereof and inwardly projecting lugs at the rear ends thereof, an insulating disk arranged in the tubular member at the rear end thereof and a second disk arranged within the tubular member and having oppositely disposed lateral projections fitting into the openings in the sides of the tubular member, said insulating disks having spaced openings, contact plates located in said openings, each contact plate having a longitudinal opening provided with 100 oppositely disposed lugs at the ends thereof, springs arranged in the openings in the contact plates and positioned upon the lugs at the ends of said openings, said springs maintaining the plates in their contact positions, 105 the rear ends of said contact plates being offset.

In testimony whereof, I hereunto affix my signature.

HAROLD C. WHITE.
